UNITED STATES PATENT OFFICE.

THOMAS D. HOOPER, JR., OF PHILADELPHIA, PENNSYLVANIA.

LETTERING-MACHINE.

1,292,320.

Specification of Letters Patent. Patented Jan. 21, 1919.

Original application filed January 26, 1917, Serial No. 144,727. Divided and this application filed May 25, 1918. Serial No. 286,446.

To all whom it may concern:

Be it known that I, THOMAS D. HOOPER, Jr., a citizen of the United States, residing at Philadelphia, county of Philadelphia, 5 and State of Pennsylvania, have invented a certain new and useful Improved Lettering-Machine, of which the following is a specification, the same being a division of my application serially #144,727, filed January 10 26, 1917.

This invention relates broadly considered to lettering machines and has more particular relation to that class of such machines which permit of printing upon flat surfaces 15 without the employment of platens and specifically relates to the escapement mechanism of a machine for lettering boxes, crates, barrel, keg and cask heads and similar articles of merchandise.

20 It is an object of the present invention to provide a lettering machine of the character stated equipped with a new and novel form of escapement mechanism, and further provide certain constructions, combinations and

25 connections of parts relative thereto. A further object of the invention is to provide a lettering machine the base ends of which are so shaped and proportioned that the machine may be readily positioned upon the 30 head of a barrel, cask or keg for printing purposes. With these and other objects in view as will hereinafter more fully appear, the invention consists of the improvements hereinafter described and finally claimed.

35 The nature, characteristic features and scope of the invention will be more fully understood from the following description taken in connection with accompanying drawings forming part hereof and in which:

40 Figure 1 is a top or plan view of the lettering machine.

Fig. 2 is a view in section taken upon the line 2—2 of Fig. 1 looking in the direction of the arrows.

45 Fig. 3 is a similar view taken upon the line 3—3 of Fig. 1 looking in the direction of the arrows, the release key being shown in dashed lines in order to illustrate its point of connection.

50 Fig. 4 is a fragmentary view in plan of the ring for supporting the inking pads.

Fig. 5 is a view in section taken upon the line 5—5 of Fig. 4.

55 Fig. 6 is a rear view of a pad holding plate.

Fig. 7 is a side view of a type-head.

Fig. 8 is a bottom view thereof.

Fig. 9 is a fragmentary view in perspective of a key-arm support.

Fig. 10 is a top or plan view of such support. 60

Fig. 11 is a view in side elevation of key-arm.

Fig. 12 is a perspective view of a key-guide. 65

Fig. 13 is a sectional view taken upon the line 13—13 of Fig. 12.

Fig. 14 is a similar view taken upon the line 14—14 of Fig. 15.

Fig. 15 is a similar view taken upon the line 15—15 of Fig. 14. 70

Fig. 16 is a view in side elevation of the base of the machine drawn to a reduced scale and mounted upon a barrel head shown in dash lines. 75

Fig. 17 is a top or plan view of the same, and

Fig. 18 is a fragmentary view hereinafter referred to.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized within the scope of the appended claims and that my invention is not limited to the precise arrangement and organization of the instrumentalities as herein shown and described. 80

85 Referring to the drawings, it will be observed that the machine embraces, broadly stated, a base made up of a pair of fixed

90 longitudinally extended rails and a releasable carriage movable therealong under spring tension. The base comprises a pair of spaced, parallel beams 10, cut away as at 95

100 13 to lighten construction and which beams are connected at each end by cross-pieces 11 formed integral therewith. The cross-pieces in plan are curved upon an arc of a circle as shown in Figs. 1 and 17 and are

105 notched as at 11' for a purpose to presently appear. Considered in elevation, these cross-pieces 11 are of substantially inverted U-

110 shape as shown in Fig. 18. The purpose of the specific form of cross-pieces disclosed is so that the beams may be rigidly connected

65

110

at their ends but still permit the base as a whole being placed upon a barrel head, it being understood that the beams 10 rest upon the head 14 of a barrel and that the 5 cross-pieces overhang the chime 14' of a barrel. Fixed upon the top of each beam 10 is a guide piece 15 of which one is toothed to provide a rack 16. These guide pieces project beyond the curved part 11' of the 10 beams so that when the beams are positioned upon a barrel head as shown in Fig. 16, the guide pieces 15 rest upon the chime 14' of the barrel and the curved ends of said beams are positioned inside of said chime. The extreme ends of said guide pieces 15 are connected by cross-pieces 15'. The guide pieces 15 are beveled upon their inner faces. Secured to the bottom of carriage 19 are parallel spaced, guide pieces 17, the outer faces of 15 which are beveled for co-operation with the beveled faces of the guide pieces 15. These guide pieces 17 do not extend beyond the carriage structure 19. These guide pieces 17 are accommodated by 20 the notched parts 11' of the cross-pieces 11 in the back and forth travel of the carriage 19. By the arrangement of parts 16-17, it will be observed that while the carriage is free to be moved back and forth, it is interlocked with respect to the base. The carriage which is adapted to move along the base under spring tension when released as will presently appear comprises a shell-like structure 19 of circular form considered in 25 plan having a removable cover 20 centrally apertured as shown. At the left hand side of the carriage there is fixed thereto an arm or projection 21 operatively supported upon which is a coiled spring 22 the free end of 30 which is secured to the righthand side of the base as at 23, see Fig. 1, it being understood that in printing the movement of the carriage is from left to right. A description will now be given of the release mechanism 35 which is designated A and is located at the back of the machine although the release key 24 is placed at the righthand side of the machine opposite the key-board 25 for convenience of operation. The key-board is 40 located immediately below the aperture in the cover. Journaled in the carriage structure 19 is a stud shaft 26 fixed upon which is a ratchet wheel 27 and a crown gear wheel 28 which latter is in mesh with a train of 45 gear wheels 29 mounted upon the underside of the carriage and in mesh with the rack 16 of the base of the machine, see Fig. 3. A pair of dogs 30 and 31 are present for co-operatively engaging with the ratchet wheel 27. The dogs are loosely mounted upon a fixed stud 32 and the dog 31 has fixed thereto an arm 33 connecting with which is a spring 34 for normally keeping said dog 50 out of engagement with the ratchet wheel 27. The free end of the arm 33 is connected by 55 means of a rod 41 with a link 41' fulcrumed to a fixed support 41'' which latter is connected to one end of a lever 42 fulcrumed to a fixed support 42'', the other end of said lever 42 being connected to a depending member 42' fixed to a freely tiltable disk 43. The normal position of the disk 43 is that shown in Fig. 2 or in other words it rests in horizontal position upon the arms 45 of keys 40 the disk being apertured at suitable places 60 to permit said arms 45 to project therethrough as shown in said figure. By depressing a key 40 as shown at the lefthand side of Fig. 3, the outer end of arm 45 tilts disk 43 which tilting through member 42', lever 42, link 41' and rod 41 raises arm 33 and causes dog 31 to move toward the ratchet wheel 27 which movement causes dog 30 to be disengaged from a tooth and permitting ratchet wheel 27 to move in the direction of 65 the arrow in Fig. 14 for the distance of one tooth whereupon the ratchet wheel is stopped by a tooth coming in contact with the dog 31. This movement permits carriage 19 to move by reason of spring 22 through the connecting crown-gear, gear wheel 28, gear wheels 29 and rack 16 for required distance along the base. With the release of a key 40, spring 34 returns arm 33 to place, thereby returning dog 30 to engagement with a 70 ratchet tooth and at the same time freeing dog 31 of tooth engagement. The two dogs are held in abutting relation by means of a spring 39. By the above operation, it will be observed that every time a key 40 is operated 75 the carriage moves a predetermined distance. In conjunction with the above movement a spacer key is necessary. The spacer key is designated 56 and is connected to an arm 57 fulcrumed upon the fixed support 44. The free end of the arm 57 when raised comes in contact with and tilts the disk 43 in the same manner as the keys 40 as above described and releases the ratchet wheel 27 for the space of one tooth as before described. Also in conjunction with the above movements, a release is required so that if it be desired to move the carriage forward, a quick action thereof may be effected. The release key 24 connects with one end of a 80 fulcrumed lever 37 the other end of which lever connects by means of a rod 37' with an arm 35 formed upon an arc of a circle, see Fig. 1, and fulcrumed as at 36. The free end of said arm is provided with a wedge-shaped 85 trip-pin 38 which normally fits loosely between the two dogs so as not to interfere with their normal workings. By depressing release key 24, arm 35 is moved around its fulcrum point 36 thereby depressing the free end thereof and causing trip-pin 38 to pass between the enlargements 38' of the dogs 30-31 and separate the same thereby freeing the ratchet wheel 27 to permit the carriage 90 to be moved any desired distance forward or 95

backward as will be readily understood. A detailed description will now be given of the connection for operating the printing devices. Fulcrumed upon the supporting structure 44 within the carriage 19 are a series of depressible levers 45 each pivotally connected at one end with a key 46 and pivotally connected at the other end with a jointed rod 46 extending to a point near the bottom of the carriage and in turn operatively connecting with a printing device B. Each printing device is pivotally supported as at 47 upon the end of an arm 48 fulcrumed as at 49 between a U-shaped socket 50 which is adjustable upon the bottom of the carriage 19, see Fig. 10. Upon each side of each arm 48, which arms are under spring tension as at 51, is a guide-rod 52 of U-shaped cross-section pivoté to a printing device B and to a socket 50. As shown in Fig. 7, each printing device comprises a block 53 the printing face of which is provided with a rubber or other impression member 54 and the back of which block 53 has adjustably mounted thereon a U-shaped socket 55 between which an arm and two guide rods are pivoted. Referring now to Fig. 3, it will be noted that in normal position an appreciable portion of the arms 45 of keys 40 rests in horizontal position upon the flat surface of support 44 so that little or no strain is exerted upon them. With depression of a key 40 a jointed rod 46 exerts a pull upon the fulcrumed end of arm 48 causing same to move against action of a spring 51 toward the opening at the carriage center in the bottom thereof. During this movement, the block 53 pivoted to the end of said arm 48 is turned over upon itself as clearly illustrated at the center of Fig. 3, the guides 52 serving not only to effect turning over of said block but, serve to maintain said block in proper vertical printing position. Such movement of an arm and block causes an impression member 54 to imprint a suitable character or letter upon the flat surface C upon which the base of the machine stands as for instance a box, crate, barrel head or the like. A description will now be given of the inking pads D of which there is one for every impression member 54. Supported at the top of carriage structure 19 is a ring 60 struck up from which are a series of spaced ears 61 disposed at an inclination and fixed to each of which is a plate 62, see Fig. 5. Secured in appropriate manner around said plate is felt or the like 63 so disposed that an ink receiving space 64 is present between said felt and plate 62. By this construction ink may be readily poured from a can into said spaces 64. As clearly shown in Fig. 2, an inking pad D is disposed in alinement with each printing device B so that when at rest or in non-printing position an impression member 54 is in abutting relation with a

pad. Regarding the ring 60 it is to be noted that ears 65 for forming means of attachment for the springs 51 are also stamped therefrom and that the openings 66 thus formed afford means for the passage through said ring of the jointed rods 46. Rods 67 serve to support the ring 60. The disk 44 is supported above ring 60 by rods 68 secured to said ring. The key-board 23 in turn is supported upon disk 44 by other rods 69. As an inspection of the drawings will show most of the parts may be stamped from sheet metal or the like thus providing a very light weight and comparatively inexpensive construction. The cover 20 being removable provides ready means of access to all working parts. It is thought that from the foregoing description the mode of operation of the machine will be obvious without further description. While I have stated that the machine is particularly adapted for use in connection with boxes, crates, barrel heads and the like, obviously, the machine is capable of use for other purposes for instance the printing of sign boards and similar articles of a flat nature.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. In apparatus of the character stated the combination of a base shaped for resting upon a box or barrel said base being provided upon its rear face with a rack, a carriage for longitudinal movement therealong, a carriage feed at the rear of the carriage provided with a vertically disposed crown wheel, a train of horizontally disposed gear wheels mounted upon said carriage and interposed between said crown wheel and rack, printing mechanism, a disk tiltably mounted in a free manner in the path of movement of the printing mechanism, a horizontally disposed lever fulcrumed to the rear of the carriage structure the forward end of which arm is connected to the central portion of said disk and the rear end of which arm is operatively connected to said feed whereby upon operating the printing mechanism said disk is tilted to operate said feed.

2. In apparatus of the character stated the combination of a base shaped for resting upon a box or barrel said base being provided with a rack upon its rear face, a carriage mounted for longitudinal movement there-

along, an escapement at the rear of said carriage provided with a vertically disposed crown wheel, a train of horizontally disposed gear wheels mounted upon the carriage and 5 interposed between said rack and the crown wheel, printing mechanism, a tiltable disk in the path of travel of said printing mechanism, a horizontally disposed arm fulcrumed to the rear of said carriage the forward end 10 of said arm being connected to said disk and means connecting the rear of said arm with said escapement for permitting movement of the escapement upon operating the printing mechanism.

15 3. In apparatus of the character stated, the combination of a base shaped for resting upon a box or barrel said base being provided with a rack upon its rear face, a carriage mounted for longitudinal movement 20 therealong, a feed for said carriage at the rear thereof provided with a vertically disposed crown wheel, a train of horizontally disposed gear wheels mounted upon said carriage and interposed between said crown 25 wheel and rack, a spacer at the front of said carriage, a tiltable disk mounted in the path of movement of said spacer and a lever fulcrumed in horizontal position beneath said

disk, the forward end of which is secured to said disk and the rear end of which is secured to said feed. 36

4. In apparatus of the character stated the combination of a base shaped for resting upon a box or barrel said base being provided upon its rear face with a rack, a carriage mounted for longitudinal movement therealong, an escapement mechanism at the rear of said carriage said escapement mechanism being provided with a vertically disposed crown wheel, released mechanism for 40 said escapement, a train of horizontally disposed gear wheels mounted upon the carriage and interposed between said crown wheel and rack, a horizontally disposed arm fulcrumed to the rear of the carriage and 45 extended partway therearound forwardly in a semi-circular fashion, one end of said arm co-operatively engaging said release mechanism and a release key operatively connecting with the free end of said arm. 50

In testimony whereof, I have hereunto signed my name.

THOMAS D. HOOPER, Jr.
